UNITED STATES PATENT OFFICE.

SIMON HEITER AND SALOMON J. LESEM, OF NEW YORK, N. Y.

DESIGN FOR AN UMBRELLA-HANDLE.

SPECIFICATION forming part of Design No. 11,698, dated March 23, 1880.

Application filed February 5, 1880. Term of patent 3½ years.

To all whom it may concern:

Be it known that we, SIMON HEITER and SALOMON J. LESEM, citizens of the United States, and both residing at New York, in the county and State of New York, have invented and produced a new and original Design for Parasol and Umbrella Handles, of which the following is a specification, reference being had to the accompanying drawing, forming part thereof.

The special feature of our design consists in a novel and peculiar volute ornamentation which forms the head of the handle.

In the accompanying drawing is seen a side elevation of the handle, which clearly illustrates the features of our design.

a represents the straight portion of the handle, which may be round or of octagonal form, as preferred. Its upper part is bifurcated, as seen at *b*, one division, *c*, curving outward in a leaf-like manner. The other section, *d*, extends up for a short distance, and takes a winding or volute-like conformation, as seen at *e*. A further elegant configuration is produced on the outer edge of this branch *d* by the gradual curves *f f*, resulting in the protuber-

ance *g* with the flattened apex *h*, which may have a slight convexity, if desired.

To add to the attractiveness of the design the circular outline or periphery of the volute may be caused to appear to the eye as slightly beveled; or, if ornamental carvings are placed on the surface, it will present an irregular and broken edge; but in either case the character of our design is not changed by such additional ornamentation.

We claim—

1. The design for an umbrella or parasol handle, consisting of the voluted and foliate ornamentations *e e*, forming the head, as described, and shown in the accompanying drawing.
2. The design for an umbrella or parasol handle, consisting of the branches *c* and *d*, forming volute and foliate ornamentations, substantially as described, and shown in the accompanying drawing.

SIMON HEITER.

SALOMON J. LESEM.
